ROLLERS

This invention relates to rollers and in particular to a roller system that may be used to apply uniform pressure to a work-piece.

In many processes a work-piece has to be passed between a pair of rollers for one reason or another. Depending on the nature of the process, such rollers have heretofore been constructed from a variety of materials including metals and rubber. Often it is desired that the rollers exert a uniform pressure on the work-piece and in such cases rollers made from a resilient material such as rubber have been used. However, such rollers are generally unsuitable for use at elevated temperatures and are also liable to uneven wear. Also they are unsuitable where it is desired that the resilient roller has a hard and/or high quality, e.g. polished surface.

In our Dutch Patent application 68,16667 we described resilient liquid filled plates which were designed to overcome disadvantages, associated with rubber and other resilient materials in a pressing process. In these plates a cushion of liquid was trapped between two thin metal sheets joined to each other round their periphery. Adaptation of this principle to a roller system would be highly desirable for use in processes wherein a work-piece has to be passed through rollers, for example as in a continuous process.

However, the mere provision of a resilient thin metal tube filled with a liquid bearing against a rigid roller would not itself be satisfactory since it would not be possible to apply any appreciable pressure to a work-piece passed between the nip of such a roller system since the resilient roller would merely deform and lessen the effective pressure.

This difficulty may be overcome by supporting the opposite side of the resilient roller to the nip through which the work-piece passes by another one or more further rigid rollers. Thus the resilient roller may be mounted as a member of a roller train of at least three rollers so that the resilient roller is mounted and supported between at least two rigid rollers at least one of which is biased towards the axis of the resilient roller so as to apply pressure thereto.

In addition, some means has to be devised to seal the space enclosed by the thin metal tube. If the ends of the tube are attached e.g. by welding, to rigid end plates, the ends of the resilient roller will be appreciably more rigid than the middle portion of the roller with the result that the deformation that could be permitted by such a resilient roller would vary over the length of the roller.

This latter problem can sometimes be overcome by making the resilient roller appreciably longer than the rigid rollers so that the ends of the resilient roller extend beyond the ends of the rigid rollers for a distance sufficient to accommodate the transition from the resilient mid portion of the resilient roller to the relatively rigid end portions of the resilient roller.

However, attaching the tube ends e.g. by welding to rigid end plates is an inherently impracticable method of sealing the space enclosed by the tube and problems such as differential thermal expansion arise. Such seals are also not particularly robust and the seals often burst when the resilient roller is being used.

We have now devised a more practicable and more robust form of resilient roller construction that removes the necessity for the ends of the tube of the

resilient roller to be rigidly attached to rigid end plates. When such a roller is used it is not always necessary for its ends to extend beyond the ends of the rigid rollers.

Accordingly, we provide a resilient roller for use in a roller train comprising a rigid cylindrical core member and a cylindrical thin metal sleeve surrounding said core and held spaced therefrom by resilient sealing members at either end of the sleeve, which sealing members also seal the space enclosed between the core and the sleeve, said space being filled with a filling material that is liquid under the conditions of use of said resilient roller.

The core member is preferably provided with flanges against which the sealing members may abut to prevent them being forced out of the sleeve when pressure is applied thereto. Alternatively the same object may be achieved by providing the core member with grooves in which the sealing members are located.

Any suitable sealing members may be used in the present invention. Examples of suitable members include O-rings, chevron rings and rubber rings that are attached rigidly to leaf springs. O-rings are particularly cheap and convenient sealing members and the invention will hereinafter be described in terms of O-ring sealing members although it is to be understood that the invention is by no means limited to O-rings.

The O-rings, which are preferably made of rubber, permit flexing of the thin metal sleeve while providing an adequate support for the sleeve and also a seal to contain the filling material within the space between the sleeve and the core member.

The invention is illustrated by the accompanying drawings, wherein:

FIG. 1 is a longitudinal section of a resilient roller in accordance with the invention.

FIG. 2 is a diagrammatic end elevation of a roller train incorporating a resilient roller in accordance with the invention.

FIG. 3 is a side elevation of a roller train incorporating a resilient roller in accordance with the invention.

FIG. 4 is a section of the roller train shown in FIG. 3 along the line IV — IV.

FIG. 5 is a cross section along the line V — V of FIG. 4.

The roller depicted in FIG. 1 consists of a cylindrical core member 1 and a thin metal sleeve 2 held spaced from core member 1 by two rubber O-rings 3,4. The O-rings also seal the space between core member 1 and sleeve 2.

O-ring 3 abuts against a flange 5 formed integrally with core member 1. Flange 5 has a diameter less than the inside diameter of the thin metal sleeve 2 and extends inside said sleeve 2. Adjacent to flange 5 is a second flange 6 also formed integrally with core member 1. Flange 6 has a diameter greater than the inside diameter of sleeve 2 but less than the outside diameter of sleeve 2. This flange 6 limits longitudinal movement of sleeve 2. Typically the sleeve 2 may be made of stainless steel of thickness 0.75 mm.

The other end of core member 1 from flange 6 is threaded and carries a second sleeve 7, which is shaped to correspond to flanges 5 and 6 on core member 1, and thus provides an abutment for O-ring 4 and a limit for longitudinal movement of sleeve 2. Sleeve 7 is held on the core member 1 by a nut 8.

The space 9 between the sleeve 2 and core member 1 is filled with a material that is liquid under the intended conditions of use of the roller.

The material used for the O-rings should of course be inert to the material used to fill space 9.

As mentioned above the resilient roller may be used in a roller train between two or more rigid cylindrical rollers.

Typically the resilient roller is mounted between three parallel rigid rollers with its longitudinal axis parallel to the axes of the rigid rollers, so that a work-piece to which it is desired to apply pressure can pass between one or more of the three nips between the resilient roller and the rigid roller, said rigid rollers being mounted such that, in a section in the plane perpendicular to the longitudinal axes of the rollers, the longitudinal axes of the rigid rollers lie at the corners of a triangle, and, when the work-piece is in position, the center of the resilient roller lies within said triangle and the resilient roller contacts the work-piece at each of the nips between the rigid rollers and the resilient roller through which the work-piece passes and contacts the rigid rollers at any nip through which the work-piece does not pass, the resilient roller being of such diameter that it deforms slightly at each of the three places of contact thereby applying pressure to the work-piece.

The work-piece can pass through one, two or all three of the nips between the resilient rollers and the rigid rollers. Where it passes through only one nip the resilient roller will contact the two other rigid rollers themselves; where it passes through two of the nips, the resilient roller will only contact one rigid roller; while where the work-piece passes through all three nips, the resilient roller nowhere contacts the rigid rollers themselves.

A typical roller train is depicted in FIG. 2 wherein the three rigid rollers 1,2,13,14, are shown having their axes at the corners of triangle ABC. The resilient roller 15 is mounted with its center, O, inside triangle ABC. It will be appreciated that if the center O was outside the triangle ABC, the support for the resilient roller 15 given by the rigid rollers would generally be inadequate. The work-piece 16 passes between the nip between rigid roller 12 and the resilient roller 15. The radius of resilient roller 15 is slightly greater than the radius of the circle 17 (indicated by broken lines) which circle is then inscribed between rollers 13 and 14 and the work-piece 16. Resilient roller 15, therefore is deformed at the places where it contacts the rigid rollers 13 and 14 and the work-piece 16 so that pressure is applied to the work-piece 16.

One convenient way of mounting the rollers is to mount two of the rigid rollers in fixed positions and the third rigid roller in guides so that it can be biassed, e.g. by means of springs or weights, towards the center of the resilient roller. The resilient roller, being supported by the rigid rollers, needs no mountings to take lateral thrusts but should be provided with thrust bearings to take longitudinal thrusts. Such thrust bearings may conveniently take the form of an oilite washer or a plate of low friction material such as polytetrafluoroethylene against which the ends of the core of the resilient roller engages.

In a preferred form the two rigid rollers mounted in fixed positions are the same size and the third roller,

which may also be the same size, is mounted such that in the plane perpendicular to the axes, its longitudinal axis is at the apex of an isosceles triangle with the axis of the two other rigid rollers at the base corners of the triangle. In some cases the resilient roller can also be mounted in guides, both the resilient roller and the rigid roller at the apex of the triangle being capable of movement in a line perpendicular to the base of the triangle.

10 Where the resilient roller is mounted in guides, if the work-piece is thin, in comparison to the radius of the rollers, it is immaterial through which nip or nips the work-piece passes in such a system. However, if the work-piece is relatively thick, to avoid undue stresses at the mountings of the resilient roller the work-piece should pass through the nip between the rigid roller at the apex of the triangle and the resilient roller, or through both of the nips between the rigid rollers at the base corners of the triangle and the resilient roller, or through all three of the nips so as to provide a symmetrical system.

15 In a system where a thick work-piece is to be passed through one of the nips between the rigid rollers at the base of the triangle and the resilient roller, then it may be desirable, to avoid such stresses, to reduce the radius of that rigid roller by an amount equal to the thickness of the work-piece. Such stresses do not arise if the resilient roller, is only provided with thrust bearings to take longitudinal thrusts. A suitable roller train system is shown in FIGS. 3 to 5.

20 In this system three rigid rollers 18,19,20 are mounted with their longitudinal axes parallel with the axes 21,22,23 at the corners of an isosceles triangle as shown in FIG. 3. Rollers 18 and 19 have the same radius while roller 20 has a radius less than that of rollers 18 and 19 by an amount equal to the thickness of the work-piece 24. The axis 21, i.e. that of roller 18, is at the apex of the isosceles triangle, while axes 22 and 23 are at the base corners of the triangle. Rollers 19 and 20 are mounted in fixed positions in a frame 25 whereas the mounting 26 for roller 18 is movable in a slot 27 in a direction perpendicular to the base of the triangle and can be adjusted by means of screws 28.

25 The resilient roller 29, which has a construction of the type depicted in FIG. 1 but with the O-rings located in grooves in the core member is supported by rollers 19 and 20 and is provided with thrust bearings 30 in the form of pads of polytetrafluoroethylene fastened to frame 25 and against which pads the ends of the core of roller 29 bear.

30 As stated hereinbefore, it is not always necessary, for the ends of the resilient roller to extend beyond the ends of the rigid rollers to accommodate the transition from the resilient portion of the resilient roller to the rigid end portions, since the whole length of the thin metal sleeve is resilient. Indeed to prevent the thin metal sleeve from swelling, which would reduce the effective pressure applied and possibly give rise to bursting or leaking at the ends of the sleeve, we prefer that the rigid rollers are longer than the distance apart of the O-rings supporting the thin metal sleeve.

35 In the system depicted in FIGS. 3 to 5, the rigid rollers 18,19,20 are shown to be of the same length as the thin metal sleeve 31 or resilient roller 29. Provided the flanged end portions of resilient roller 29 (correspond-

ing to portions 6 and 7 of the roller in FIG. 1) do not have a diameter greater than the circle inscribed between the rollers 18 and 19 and work-piece 24 when the desired pressure is applied, the rigid rollers can extend over these flanged portions if desired. However, there is little advantage in so doing as the useful nip length is of course limited by the length of the thin metal sleeve 31. Preferably the width of the work-piece 24 is the same as or greater than the distance between the O-rings supporting the thin metal sleeve 31 so as to avoid permanent distortion of the sleeve 31.

In a system of more than three rigid rollers, the resilient roller must be made larger in order to engage with all the rigid rollers. Increasing the size of the resilient roller requires the use of thicker gauge metal for the tube in order to contain the pressure developed in the filling material. In such a system of more than three rigid rollers it is to be understood that the center of the resilient roller should lie within the polygon formed by the longitudinal axes of the rigid rollers in a plane perpendicular to those axes.

The resilient roller may be subjected to relatively high pressures, depending on the application envisaged, and so of course has to be constructed to have adequate strength. For this reason, particularly where relatively high pressures are required, it is preferred to make the tube of this resilient roller from a metal such as high tensile steel (which may be made rust resistant if necessary), high tensile alloy steel or a spring steel so that the wall thickness can be kept at a sufficiently low value to provide adequate resiliency.

Preferred resilient roller diameters are in the range 3 to 10 cm, preferably less than 5 cm. The wall thicknesses are preferably in the range 0.03 to 0.3 preferably less than 0.1 cm and particularly 0.05 to 0.08 cm. The thickness of the layer of the liquid filling material is preferably within the range 0.01 to 0.35 cm, particularly within the range 0.025 to 0.08 cm. It is also preferable that the roller be pre-pressurized, i.e. filled with a filling material under pressure.

The material used to fill the resilient roller has to be one that is liquid or rubbery under the conditions of the rolling operation. It is not necessary, however, that it is liquid at room temperature if the rolling is performed at an elevated temperature and in some cases therefore the filling material may be material that is solid at room temperature but having a melting point below the rolling temperature.

The possibility of the use of a filling material that is solid at room temperature permits the use of some metallic materials as the filling material, thereby enabling advantage to be taken of the superior thermal conductivity of metals over non-metallic filling materials such as oils and waxes where heat has to be conducted to the work-piece through the filling material.

Where a filling material that is solid at room temperature is used, it is preferred, however, that the melting point of the filling material is substantially lower than the rolling temperatures so that is ensured that all the filling material is liquid at the rolling temperature.

Since there is little advantage in the use of a higher melting solid, the filling material should have a melting point below 120°C preferably below 100°C.

Solids that can be used as filling materials in appropriate cases include organic compounds such as

waxes and some metals, particularly some alloys of bismuth, lead, tin and/or cadmium.

The use of a filling material that is solid at room temperature has some disadvantages, particularly in relation to the operation of filling the rollers as it is generally necessary to fill the roller with the filling material in the liquid state to ensure complete filling. With the use of a filling material that is solid at room temperature this means that the filling operation is complicated by the necessity of the use of associated heating apparatus.

We therefore in general prefer to use a filling material that is liquid at room temperature, i.e. at about 18°C.

Preferred filling materials include mineral oils, water, silicone oils, glycol and glycerol.

Glycerol, while having a reasonably good thermal conductivity has the disadvantage that some steels and hence rollers made therefrom, catalyze the decomposition and polymerization of glycerol.

This however, can be minimized by incorporating a suitable stabilizer in the glycerol, for example, borax or 1,1,3-tris-(3-t-butyl-4-hydroxy-6-methyl phenyl) butane.

Indeed, with any liquid, suitable stabilizers may be incorporated as necessary, e.g. sodium nitrite may be added to water to inhibit rust formation when water is used to fill ferrous metal rollers.

Water is generally satisfactory and is the preferred filling material as, for a liquid, it has a good thermal conductivity. However, because of its relatively low boiling point its use is generally limited to rolling temperatures below about 250°C or else unnecessarily high pressures are required to maintain the water in the liquid phase. For higher temperature work, glycol, glycerol or silicone or mineral oils may be used. However, because silicone and mineral oils have a poor thermal conductivity but are otherwise satisfactory, they are preferably only used as the filling material in rolling operations where no reliance is placed on the filling material to conduct heat to or from the work-piece.

If desired, solid materials or other liquids may be mixed with the filling material provided they remain uniformly dispersed in the filling material in order to improve its thermal conductivity properties.

The rigid rollers may be solid or may be nonresilient tubes suitably provided with means for mounting. While one object of the rollers of the present invention is to avoid the use of rubber faced rollers, in some cases it may be possible and advantageous, particularly where it is necessary that the work-piece is gripped as it passes through the nip, to form the rigid roller or rollers from a resilient material such as rubber or provide a rigid metal roller with a thin coating of a resilient material such as rubber. If desired the resilient roller may be heated or cooled for example by passing steam or water through a heating coil inserted in the filling material.

Examples of uses of the roller train are in the production of sheets, films and extruded foil of plastic materials; coating sheet material such as paper or plastic films with coatings of, for example, plastic materials; continuous lamination processes; and in the production of bonded fabrics. When high quality plastics sheet is desired it is often necessary to use rollers having highly polished surfaces.

The roller trains of the present invention are of particular utility in the production of bonded non-woven fabrics from synthetic filaments. As an example, the filaments, which may conveniently be bicomponent filaments having, for example, a nylon 6.6 core and a nylon 6.6/nylon 6 copolymer sheath, are extruded, optionally drawn and heat set, and a bundle of filaments is passed to a pneumatic forwarding device. The forwarding device is traversed above an advancing collecting surface whereby a web of filaments is manufactured. The web may then be bonded by passage through a nip consisting of a heated roller provided with protrusions on its surface, and a solid backing roller, whereby the web is segmentally bonded. When using the roller train of the present invention, one of the solid rollers of the train is formed as a spiked roller by providing a number of protrusions having rectangular, square or various cross-sections over all the surface of the roller at predetermined intervals. This spiked roller, which can be heated to 180°C, can be pressed against the resilient roller under a load of between 100-200 pounds per inch length of nip to give a high quality segmentally bonded fabric without causing any damage to the resilient roller.

We claim:

1. A resilient roller for use in a roller train consisting of a rigid cylindrical core member and a cylindrical thin metal sleeve surrounding said core and held spaced apart therefrom by resilient sealing members at either end of the sleeve which is inwardly deformable over the whole of its length, which sealing members also seal the space enclosed between the core and the sleeve, said

sleeve being filled with a filling material that is a liquid under the conditions of use of said resilient roller.

2. A resilient roller as claimed in claim 1 in which the core member is provided with means for limiting outward longitudinal displacement of the sealing members along the core member.

3. A resilient roller as claimed in claim 2 in which the means for limiting outward longitudinal displacement of the sealing members along the core member are flanges situated at each end region of the core member and which extend outwardly therefrom and against which the sealing members abut.

4. A resilient roller as claimed in claim 2 in which the means for limiting outward longitudinal displacement of the sealing members are grooves situated at each end region of the core in which the sealing members are seated.

5. A resilient roller as claimed in claim 1 in which the metal sleeve has a diameter within the range 3 to 10 cm.

6. A resilient roller as claimed in claim 1 in which the metal sleeve has a thickness within the range 0.03 to 0.3 cm.

7. A resilient roller as claimed in claim 1 in which the layer of filling material has a thickness within the range 0.01 to 0.35 cm.

8. A resilient roller as claimed in claim 1 in which the filling material is a liquid at room temperature.

9. A resilient roller as claimed in claim 8 in which the filling material is selected from the group consisting of mineral oil, silicone oil, water, glycol and glycerol.
